UNITED STATES PATENT OFFICE.

WILLIAM A. HARWOOD, OF BROOKLYN, NEW YORK, ASSIGNOR TO THE
MERRIAM MANUFACTURING COMPANY, OF DURHAM, CONN.

DESIGN FOR A TOY RAIL-CAR.

Specification forming part of Design No. **6,868**, dated September 2, 1873; application filed July 9, 1873.
[Term of Patent 7 years.]

To all whom it may concern:

Be it known that I, WILLIAM A. HARWOOD, of Brooklyn, in the county of Kings and State of New York, have invented a new Design for Toy Car; and I do hereby declare the following, when taken in connection with the accompanying drawings and the letters of reference marked thereon, to be a full, clear, and exact description of the same, and which said drawings constitute part of this specification, and represent, in—

Figure 1, a side view; and in Fig. 2, an end view.

This invention relates to a design for toy rail-cars; and consists in the peculiar form of the roof of the car, as shown in the accompanying drawings, and as hereinafter described.

The peculiar characteristic of the roof is the

formation of an angle between the ridge *a* and edge *b*, as at *d*. Between these points the roof is preferably made concave; yet, if preferred, the lines may be straight from *b* to *d* and *d* to *a*, or one curved and the other straight, the essential feature of the design being the three prominent longitudinal lines or angles *a b d*.

The body *A* of the car may be of any desirable form or style, my claim being confined to the configuration of the roof.

I claim as my invention—

The design for the roof of a toy rail-car, substantially as herein described and shown.

WM. A. HARWOOD.
